UNITED STATES PATENT OFFICE.

WILLIAM C. KEY, OF KNOXVILLE, TENNESSEE.

APPARATUS FOR SCALDING GRASS.

1,042,688.

Specification of Letters Patent. Patented Oct. 29, 1912.

Application filed November 25, 1911. Serial No. 662,504.

To all whom it may concern:

Be it known that I, WILLIAM C. KEY, a citizen of the United States, residing at Knoxville, in the county of Knox and State 5 of Tennessee, have invented certain new and useful Improvements in Apparatus for Scalding Grass, of which the following is a specification.

My present invention aims to provide 10 simple and efficient means whereby the locomotive of a work train or any other locomotive may be equipped with an attachment for forcing, under considerable pressure, hot water down in between the crevices of the 15 stones or the like composing the ballast, the hot water being supplied from the boiler through the ordinary blow-off cock by means under the control of the engineer or fireman in the locomotive cab, and serve to effect- 20 ually kill the roots of the weeds, not only between the rails and the intervening portions of the cross ties, but also outside of the rails on the banks of the ballast.

The invention has for a further object 25 improved means of this character and for this purpose which may be easily applied to any locomotive without any changes in the construction thereof or without in anywise interfering with the full power or working 30 capacity or any of the ordinary functions of the engine.

With these and other objects in view as will more fully appear as the description 35 proceeds, the invention consists in certain constructions and arrangements of the parts that I shall hereinafter fully describe and claim.

For a full understanding of the invention 40 reference is to be had to the following description and accompanying drawing, in which:

Figure 1 is a side elevation illustrating 45 the application of my apparatus. Fig. 2 is a detail elevation of the discharge pipe; and Fig. 3 is a fragmentary view thereof.

In carrying out my invention I provide 50 a discharge pipe 1 which is preferably constructed in two sections joined together by a coupling 2 in which preferably there is a three-way valve 3, so that either one or the other of the sections, or both of them, may be used, as the particular requirements of the case may demand. The ends of the discharge pipe 1 have upwardly curved pipe

sections 4 connected thereto, the outer ends 55 of which are preferably closed by screw plugs 5 or the like. All of these parts are made of relatively strong metal, able to well withstand the relatively high pressure of the hot water and steam forced therethrough, 60 the same issuing through orifices 6 formed in the discharge pipe 1 and in the upwardly curved ends 4 thereof, the orifices in said ends insuring that the hot water and steam shall be deflected downwardly and out- 65 wardly in an oblique direction so that the liquid will be forced into the banks of the ballast outside of the rails, as well as in between the rails and between the cross ties. This discharge pipe 1 is secured in suspend- 70 ed relation to the rear frame braces 7 of the locomotive, being suitably braced as indicated at 8, the discharge pipe being prefer- ably held at a distance above the track rails equal to the elevation of the pilot nosing, 75 whereby it will be held relatively close to the rails to prevent the hot water and steam from being deflected by a high wind, while at the same time the discharge pipe will not be low enough to interfere in anywise with 80 the travel of the locomotive.

The discharge pipe 1 is connected by a pipe 9 extending forwardly from the three-way valve 3 underneath the ash pan of the locomotive and upwardly, as shown, the 85 forward and upwardly projecting end of the connecting pipe 9 being joined to the ordinary blow-off cock 10 of the boiler. To open the blow-off cock so as to permit the hot water to be forced at high pressure 90 down through the pipe 9 and out through the discharge pipe 1, I have in the present instance secured to the handle 11 of the cock a link rod 12, the latter extending up through a slot in the running board 13 and 95 having its upper end pivotally connected to one arm of a bell crank lever 14 fulcrumed at its elbow on said running board. The other arm of the lever 14 is connected to the forward end of an actuating rod 15, 100 extending rearwardly into the locomotive cab and provided with any desired form of handle, whereby by pulling upon the actuating rod the blow-off cock 10 will be opened and hot water and steam discharged upon 105 the road bed.

The device may be installed very cheaply and with very little labor on any locomo-

tive without interfering in anywise with any other functions of the engine, and is composed of very few parts that may be easily assembled and readily operated whenever required.

I am aware that it has heretofore been proposed to kill grass or weeds on the road-beds of railways by the use of steam or hot water or steam and hot water combined, by 10 the use of specially devised locomotives or attachments thereto that compelled changes in the construction of the boilers or other parts of the engine, and hence do not claim the same; but it is to be particularly noted 15 that with my present invention no changes whatever are required in the locomotive, it being only necessary to attach the discharge pipe to the framework of a locomotive, say to the rear frame braces, and to couple the 20 connecting pipe 9 to the blow-off cock 10 and to then merely assemble the bell crank lever 14, the link 12, and the actuating rod 15.

Having thus described the invention, what is claimed as new is:

The combination with a locomotive having a boiler provided with a blow-off cock, of a transverse discharge pipe suspended upon the locomotive in rear of the wheels thereof and projecting laterally beyond the 30 planes of the wheels, said pipe having a longitudinal series of jet openings in its bottom and having its laterally projecting end portions upturned and provided with series of jet openings to extend the spread 35 of the spray, closures in the extremities of said upturned portions, a connection between said discharge pipe and the blow-off cock, and means for operating said blow-off cock.

In testimony whereof I affix my signature in presence of two witnesses.

WILLIAM C. KEY. [L.S.]
